THOMAS A. CARTER, OF LOS ANGELES, CALIFORNIA.

WATER JET.

Application filed August 17, 1927. Serial No. 213,557.

My invention is a water jet of a self-cleansing type.

In water jets or devices for allowing flowing of a small amount of water in a more or less steady stream, it has been found that either the jet or some part of the device connected to the jet becomes clogged with sediment or the like or with marine growths which obstruct and prevent the proper functioning of the jet. This is especially true in connection with sewer flushers in which usually the water feed pipe has a valve to regulate the flow of water, in accordance with the frequency with which the sewer is to be flushed, and some of which have an outlet jet, or the like. In this instance it has been found that the outlet of the water becomes clogged with an accumulation of different marine growths or by sediment, thus preventing the proper functioning of the jet and of the sewer flushing mechanism, or other mechanism with which the jet is associated.

An object of my invention therefore, is to produce a water jet which, on account of having a moving element therein subjected to water pressure, keeps the water jet clear of marine growths, sediments or other obstructions, and hence gives a properly regulated flow.

In constructing my invention, I attach the water jet to the infeeding water pipe which may also have a regulating valve in the flushing chamber or at some other accessible place. The water jet comprises a hollow structure having a valve seat with a central bore in the seat to allow forward passage of water, and above the valve seat there is an agitation chamber in which is located a ball, this ball resting on the seat. There is a lateral orifice from this chamber which has a small port preferably on the inside, and this is enlarged outwardly, giving a cone shaped orifice with the large end outwardly. The ball is preferably inserted in the chamber by means of having a removable plug at the top. In the action of the water jet, the pressure of the water flowing through the bore at the valve seat agitates the ball and keeps a more or less continuous movement of the ball in the agitation chamber, thereby preventing accumulation of dirt, sediment or marine growths.

My invention is illustrated in the accompanying drawings, in which:

Figure 1 is a vertical sectional view through

an automatic sewer flusher, showing my water jet secured to the intake pipe.

Figure 2 is a side elevation of the water jet.

Figure 3 is a vertical section through the water jet.

In the particular type of sewer flusher illustrating the use of my water jet, a pit 11 is formed by the side walls 12 and the base 13, with a floor 14 elevated above the base on the frame 15. This leaves a chamber 16 below the floor in which a sewer 17 may discharge and empty by the pipes 17 and 18. The chamber 19 above the floor is the flushing chamber 70 and designed to become filled with water up to the desired level. The construction illustrates a hollow stand 20 through which operates an actuating rod 21 which is connected to the trap 22 pivoted on the frame 23. This trap becomes filled with water by its overflowing the stand and overcoming the weight of the valve bell 24 which is suspended by a bell operating link 25 connected to the balancing lever 26 which is pivoted on an arm 27 connected to the stand, this arm also being connected to the operating rod 21. The above features are typical of the old construction.

The water infeeding pipe for flushing 28 extends through the walls 12 and may have a hand controlled valve 29 thereon. This valve as shown in the flushing chamber, it is to be understood, may be placed in any suitable position to control the flow of water. An elbow 30 is indicated as secured to the valve 90 and is turned upwardly, and to this is attached my water jet which is designated by the numeral 31.

This water jet comprises a tubular body 32 screw threaded externally at the outside on the lower end 33, and having internal threads 34 at the top for screwing a plug 35 therein. The tubular body has a partition structure 36 which is preferably coned inwardly as indicated at 37, and also having an inclined upper surface 38. There is a bore 39 through this partition and the upper surface adjacent the bore may be regarded as a valve seat 40 on which a ball 41 forms a closure.

The chamber in which the ball is located 105 may be designated as an agitation chamber 42. An orifice 43 is formed by a port 44 of small bore, and this bore connecting with a conical outlet 45, forms an outlet from the agitation chamber 42 to the flushing chamber 19. It is to be understood that the port 44 is made in different diameters of accurate

dimensions, and that the various water jets are utilized with different automatic flushing systems in accordance with the flow of water desired.

- 5 The manner of operation and functioning of the water jet is substantially as follows. The inlet of water through the pipe 28 is regulated manually by the valve 29. This valve however, need not be so accurately adjusted as when no regulator is used. The water discharged from the valve being under pressure, shifts the ball 41 on its seat and causes this ball more or less to be agitated or bounce on the valve seat in the agitation chamber. The agitation chamber is always full of water as the port 44 is of insufficient diameter to flow the water out as fast as it passes through the bore 39. Therefore, on account of the substantially continuous movement of the ball 41, any sediment is maintained agitated and marine growths are prevented, thus at all times giving a proper flow of water to fill the flushing chamber 19 in the desired time intervals, and therefore flush 25 the sewer as required. If it is found that the sewer flushes too often, a water jet may be installed having a smaller bore at the orifice, or if it does not discharge frequently enough, this port 44 may be enlarged or a 30 water jet substituted with a larger opening. Thus an accurate control may be had of the flow of water into the flushing system.

A characteristic feature of my invention is that the ball forms, in effect, a ball valve resting on the inclined seat or surface 38 and forming a closure for the bore 39. This ball must be bodily removed before liquid can flow into the agitation chamber 42, and such action of bodily movement of the ball manifestly dislodges any dirt or sediment from the seat adjacent the bore 39. In addition, when the ball is subjected to violent movement it rubs and impinges against the inside of the port 44 thus dislodging any dirt therefrom and allowing free flow of water; and also any small sediment in the water is maintained agitated so that it may readily flow out of the discharge port 44.

Another characteristic feature of my invention is that the ball has a free movement between the seat 38 and the inner surface of the plug 35; and also that the agitation chamber 42 is of a fixed size, it being intended that the plug 35 be screwed to its full extent into the internal threads 34.

My water jet construction is essentially designed and intended to operate with a very small jet orifice having an outlet port so small that it is apt to be clogged by sediment. Therefore the ball rolling around in the agitation chamber dislodges this sediment.

Another characteristic feature of my invention is that the partition having the inlet bore has a downwardly inclined upper surface so that the ball may readily roll and the incoming flow of water causes the ball to roll on different sides of the central inlet bore.

Various changes may be made in the principles of my invention without departing from the spirit thereof, as set forth in the description, drawings and claims.

I claim:

1. A water jet comprising in combination a tubular body structure having a central agitation chamber with a transverse partition, a small outlet port through one side of the tubular body from the agitation chamber, a large ball in the agitation chamber but slightly smaller than the diameter of such chamber, a small bore through the partition forming an inlet, said bore being but a fraction of the size of the cross sectional area of the ball, and the said inlet bore being slightly larger than the outlet port and a closure for the tubular body.

2. A water jet comprising in combination, a tubular body having a cylindrical inside surface, a transverse partition at the bottom of the tubular body having a downwardly and inwardly inclined surface terminating in a central small bore, a small orifice through the side of the body, said port being minute in comparison with the diameter of the inside of the tubular body, a large ball resting on the inclined surface of the partition, the diameter of the ball being but slightly less than that of the inside of the tubular body and a closure for the upper end of said body.

3. A water jet, comprising in combination a tubular body having an inside cylindrical surface, a transverse partition having an inwardly and downwardly inclined upper surface terminating in a central small bore, such bore being a small fraction of the diameter of the inside of the tubular body and there being an outwardly and downwardly inclined surface on the lower part of the partition from the bore, a small discharge port through one side of the tubular body terminating at the outside in a cone-shaped orifice, the said port being minute in diameter compared with the diameter of the inside of the tubular body, a ball adapted to rest on the inclined surface of the partition, said ball being but slightly less in diameter than the diameter of the inside of the tubular body and a closure plug for the top of said tubular body.

In testimony whereof I have signed my name to this specification.

THOMAS A. CARTER.
